UNITED STATES PATENT OFFICE.

VICTOR YORK, OF LOS ANGELES, CALIFORNIA.

ROTARY DISK BIT.

Application filed May 3, 1923. Serial No. 636,361.

My invention relates to the art of drilling oil wells by what is known as the rotary system in which a bit is secured to the bottom of a string of drill pipe which is rotated by power applied usually at the derrick floor. The invention relates more particularly to the bit used in such drilling.

These bits are of various forms and this invention relates more particularly to what is known as disk bits in which disks are used to do the actual cutting, these disks being so mounted that they are free to turn on pins carried by disk supporting members. Such disk bits tend to cut around the periphery of a hole leaving an upwardly projecting central core. Due to this projecting core, disks cannot be used in certain types of geological structures.

It is an object of my invention to provide a disk bit with a cooperating central cutting member which operates upon this central core thus increasing the field of usefulness of such a bit and making it possible to use it in formations to which it cannot at present be applied.

In the drilling of wells, and especially oil wells, it is desirable to keep a record of the penetrated subterranean structure, this being done by employing what is known as a core drill. This core drill has a core barrel provided therein and has cutting elements at the lower end thereof which sink the hole, leaving a central cylindrical core which extends into the core barrel. The core is raised to the surface with the core bit where it is removed therefrom and is kept as a record of the penetrated strata.

It is a further object of my invention to provide means by which cores may be taken during the ordinary drilling of the hole, thus obviating the necessity of using separate devices for drilling and core taking. This I accomplish by using the disk bit to cut the periphery of the hole about the core which is then cut and removed by a cooperating cutting means carried inside the disks. This relieves the core taking portion of the bit as the majority of the cutting is done by the disks. One of the objections to the present form of disk bit is the liability of the pins to become loosened thus releasing the disks, which fall into the bottom of the hole. The disks are of a very awkward shape so that when wedged in the bottom of the hole, they cannot be readily fished. The disks are usually made of

manganese steel and are both hard and tough so that they are very hard to drill up when so lost.

It is an object of my invention to provide means in a disk bit for locking the pins in place by an auxiliary central member.

Additional advantages of the invention and further objects thereof will be made evident hereinafter.

Referring to the drawing which is for illustrative purposes only:

Fig. 1 is an elevational view of a disk drill embodying the features of the invention.

Fig. 2 is a bottom view of the drill shown in Fig. 1.

Fig. 3 is a perspective view of a wrench which may be used for installing or removing the core barrel.

In the form of the invention shown the disk bit 11 consists of head having a shank 12, which has a pin 14 at the upper end thereof for attachment to the drill pipe and having downwardly extending disk supporting arms 16 formed integral at the lower end thereof. As shown in Fig. 2 the arms 16 are offset so that the cutting edges of the disks 17 which are rotatably mounted on the inner sides of the arms 16 on the pins 18 will cut a hole represented by the broken line 19. Screwed to the body 11 at 20 is a member 21 which is positioned concentrically with the axis of rotation of the drill and which extends between the disks 17. The member 21 has teeth 23 at the lower end thereof for producing a core which will enter the central bore 24 of the member 21. The member 21 may be screwed to or unscrewed from the body 11 by placing the cylindrical portion of the wrench 26 in the bore 24 of the member 21 so that lugs 27 of the wrench 26 coincide with the slots 29 in the member 21 and by turning the wrench in the proper direction. Lubricating mud or water may be supplied to the cutters through the channels 31 provided therefor.

In the operation of the ordinary disk bit, which consists of the members 11 to 19, as described above, there is a tendency to cut around the periphery of the hole, leaving a central roughly cylindrical core projecting up inside the disks 17. This core may break off from time to time along the plane of the formation, but in some types of formation it may build up until it supports a

considerable portion of the weight of the bit and pipe, thus limiting the cutting action of the bit. The large cylindrical members formed by the cores also, when broken off, are secured to the drill pipe.

5 tend to jam the disks 17 and interfere with the operation of the bit.

By using the member 21 these cores are cut away at their base and fracturing along the plane of formation are withdrawn with 10 the bit, thus preventing the formation of high cores or their presence in the well after they become detached. The cores when removed give the driller and geologist very valuable information as to underground 15 conditions.

15. The member 21 also acts as a locking means for the pins 18 preventing them from backing out of the arms 16 if they become unscrewed.

20 When the bit is removed from the well, the packed core carried in the member 21 can be readily removed by unscrewing this member from the shank 12 by using the wrench 26. The member 21 is of substantial 25 ly uniform bore, except for the small slots 29 and, after it is unscrewed from the shank 12, the core can be readily pushed therefrom.

I claim as my invention:

30 1. A disk bit comprising: a body adapted to be secured to a string of drill pipe; arms formed on said body and projecting downwardly therefrom; two pins, one threaded in, and projecting inwardly from the inner side 35 of one of said arms, and the other threaded in, and projecting inwardly from the inner side of the other of said arms; two disks, one turning freely on one of said pins and the other turning freely on the other of said pins; and a stationary cylindrical locking member between the heads of said pins so placed as to prevent said pins from unscrewing.

2. A disk bit as in claim 1, in which said 45 locking member is also secured to said body.

3. A disk bit as in claim 1, in which said locking member comprises: a member

screwed into said body between said legs and projecting downwardly between said pins and adapted for removal while the bit is secured to the drill pipe.

4. A disk bit comprising: a body adapted to be secured to a string of drill pipe; arms formed on said body and projecting downwardly therefrom; two pins, one threaded in, and projecting inwardly from the inner side of one of said arms, and the other threaded in, and projecting inwardly from the inner side of the other of said arms; two disks, one turning freely on one of said pins and the other turning freely on the other of said pins; and a stationary locking member between the heads of said pins so placed as to prevent said pins from unscrewing, said locking member consisting of a pipe centrally secured to said body and projecting downwardly between said pins.

5. A disk bit as in claim 4, in which said pipe is provided with cutting surfaces at its lower end.

6. A disk bit comprising: a body adapted to be secured to a string of drill pipe; arms formed on said body and projecting downwardly therefrom; two pins, one threaded in, and projecting inwardly from the inner side of one of said arms, and the other threaded in, and projecting inwardly from the inner side of the other of said arms; two disks, one turning freely on one of said pins and the other turning freely on the other of said pins; and a stationary locking member between the heads of said pins so placed as to prevent said pins from unscrewing, said locking member consisting of a pipe centrally secured to said body and projecting downwardly between said pins, said pipe being provided with cutting surfaces at its lower end and being so secured in said body as to be readily removable therefrom.

In testimony whereof, I have hereunto set my hand at Los Angeles, California, this 27th day of April 1923.

VICTOR YORK:
